UNITED STATES PATENT OFFICE.

ARTHUR M. SNYDER, OF FAIRFIELD, IOWA.

INTERNAL-COMBUSTION ENGINE.

1,273,285.

Specification of Letters Patent. Patented July 23, 1918.

Application filed November 6, 1917. Serial No. 200,528.

To all whom it may concern:

Be it known that I, ARTHUR M. SNYDER, a citizen of the United States, and a resident of Fairfield, in the county of Jefferson and State of Iowa, have invented certain new and useful Improvements in Internal-Combustion Engines; and I do hereby declare the following to be a full, clear, and exact description of the invention, such as will enable others skilled in the art to which it appertains to make and use the same.

This invention relates to improvements in internal combustion engines and more particularly to that type of rotary engines which employ a plurality of cylinders with reciprocating pistons,—one object of the invention being to provide an internal combustion engine capable of developing great speed with a minimum expenditure of motive fluid.

A further object is to construct the engine in such manner that the amount of power developed may be readily regulated and controlled by the operator according to varying conditions.

A further object is to provide an internal combustion engine which shall be especially useful with aeroplanes where great speed and power are required, and which shall also be adaptable for use with automobiles, tractors and for other purposes.

With these and other objects in view, the invention consists in certain novel features of construction and combinations of parts as hereinafter set forth and pointed out in the claims.

In the accompanying drawings; Figure 1 is a longitudinal sectional view of an internal combustion engine embodying my improvements; Fig. 2 is a view partly in section and partly in elevation; Fig. 3 is a transverse sectional view through a pair of the cylinders, and showing the piston connections and the valve mechanism; Fig. 4 is an end view showing the gearing, and Figs. 5 and 6 are enlarged sectional views illustrating the valve mechanism.

The stationary framework of the engine comprises heads *b* and *d* separated sufficiently to accommodate the rotary member of the structure, and a central shaft *D* connecting said heads and passing centrally through said rotary member. The said ro-

tary member comprises a cylindrical casing *M* in which the operating mechanism is enclosed, and near one end of said casing a diaphragm or inner head *M¹* is located, whereby a chamber *M²* is formed at this end of the cylinder in which gearing hereinafter described, is located and within this chamber, suitable oil may be placed for lubricating said gearing and the movable parts connected therewith. The head *M³* of the casing (which head also forms one end wall of the chamber *M²*) is provided with a hub *j* mounted within the head *b* of the fixed frame and also on the end portion of the fixed shaft *D*,—said hub *j* being provided at its outer end with a flange or plate *M⁴* adapted to be secured to a propeller or other device to be driven. The other end of the rotary casing is provided with a head or drum *N³* having annular grooves to receive annular ribs or flanges *N²* on the head *d* of the fixed framework, and thus effect a working fit between these parts.

Located within the revolvable casing *M* are several pairs of cylinders *A* having cooling ribs *N*,—the cylinders of each pair being located at respective sides of the fixed central shaft *D*, and within each cylinder *A*, two pistons *B* are located and adapted to reciprocate in directions opposite to each other, the motive fluid being admitted to and exhausted from the central portions of said cylinders in a manner hereinafter explained, and spark plugs *P* are suitably located for igniting the explosive mixture between pistons.

Two shafts *E*, *E¹*, are mounted near their respective ends in bearings in the head or drum *N³* and in bearings afforded by the inner head or diaphragm *M¹*,—said shafts *E*, *E¹*, being caused to project beyond their bearings in the latter and terminate within the gear chamber *M²*, as shown in Fig. 1.

Cross-heads *C*, *C¹* are secured to the respective shafts *E*, *E¹*—a number of such cross-heads being secured to each of said shafts corresponding in number to the number of pairs of cylinders *A* which may be employed. In the drawing, I have shown four pairs of such cylinders but it is evident that a greater or less number may be employed. The respective ends of each cross head *C* are connected, by links *F* with the upper pistons *B* (as viewed in Fig. 3) in

two opposite cylinders A,—said links being pivotally connected at G with the cross-head and at H, with said pistons. The lower cross-head C¹ (as viewed in Fig. 3) is connected with the lower pistons B in the same cylinders.

Crank shafts Z are mounted in suitable bearings in the heads M¹ and M³ so as to be disposed within the chamber M² of the revoluble casing M and to each of these crank shafts, a gear Y is secured. These gears are thus disposed at opposite sides of the central fixed shaft D and mesh with a smaller gear e secured to the latter. Arms 10 X are secured to the respective shafts E, E¹ and to these arms, links H⁴ are pivotally connected, as at f,—the other ends of said links being attached, as at f¹, to the crank shafts Z.

With such construction and arrangement of parts as above described, it will be apparent that when gaseous charges are exploded alternately in two opposite cylinders A, the pistons in one of said cylinders will be forced in opposite directions while the pistons in the other cylinder will be caused to approach each other. In this manner the cross heads C and C¹ will be caused to oscillate, which motion will be transmitted, 25 through the shafts E, E¹ to the arms X. These arms, having link connection with the crank shafts Z, the latter will be rotated and motion will thus be imparted to the gears Y. As the smaller gear e with 30 which the gears Y mesh, is secured to the fixed shaft D, the result will be the rotation of the casing M and the mechanism therein constituting the rotary member of the engine.

40 Valve casings S^2 are located between the cylinders A of each pair and the latter are provided centrally with suitable inlet and exhaust ports communicating with the valve casings so as to receive motive fluid from the latter and also discharge the exhaust through said valve casing,—the valves in said casing being so operative that while motive fluid is being supplied to one cylinder, the exhaust products of combustion will 45 be discharged from the other cylinder. Thus in Fig. 5, an inlet valve h is shown open and in Fig. 6, the inlet valve h is shown open and the exhaust ports and its valve h for the same cylinder is shown 50 closed. In Fig. 3, I have shown the exhaust valve h' for the right hand cylinder open, and the inlet valve h for the left hand cylinder will be open as indicated in Fig. 5. The valves for the several pairs of cylinders are maintained normally closed and 55 returned to such position by means of suitable springs S^3 and they are opened in proper succession by means of cams R on a shaft T,—suitable pivoted levers being interposed between the stems of said valves and 60 65

the cams. The cam shaft T is mounted in suitable bearings in the heads M¹ and N³ and is provided within the chamber M², with a gear E² which receives motion from a gear E³ on one of the crank shafts Z, 70 when the revoluble casing and the mechanism contained therein are in motion.

The head d of the fixed frame-work may support a suitable carburetor F^1 and manifold F^4 and the latter communicated with a 75 duct S^1 in the head or drum N^3 . The duct S^1 is connected by means of a pipe A^7 with a tube I and with a sliding valve tube J located within the tube I . The tube I is provided with ports, such as indicated at 80 L^4 to communicate with the several valve casings S^2 , and the valve tube J is provided with parts L^2 of various lengths, so that when said valve tube is moved longitudinally the ports leading to the several valve 85 chambers S^2 may be opened or closed successively. In this manner the several pairs of cylinders or engine units may be thrown into or out of action successively as occasion may demand in varying the speed and 90 power of the engine under varying circumstances and conditions which may be met in practical use and operation of the engine when applied to an aeroplane or other machine.

To provide effective and compact means for manually controlling the valve tube J, the devices now to be described may be employed: A foot lever D² is pivoted at F² to the fixed head d of the framework and between its ends, said lever is pivotally connected, as at F³ with a ring or collar E⁴. Rods C³ are connected with the ring or collar E⁴ and extend through the heads d and N³,—said rods being secured at their inner ends to a grooved collar E⁵ mounted to slide on the fixed central shaft D. A collar E⁶ is revolvably mounted on the collar E⁵ and with said revoluble collar, a lever B⁴ is pivotally attached. The lever B⁴ is pivoted at E⁷ to the hub portion of the head or drum N³, and its free end is connected by a rod B² with an arm B⁵ secured to the valve tube J and passing through a suitable elongated slot in the outer tube I. It will be apparent that by operating the foot lever D², the valve tube J will be moved longitudinally within the tube I to cut the engine units out of or into service successively, according to the direction in which the valve tube is moved.

The exhaust ports for the several pairs of cylinders are adapted to discharge through the various valve casings into a tube D¹ and this tube, communicates through a duct N¹ 125 in the head N³ with one end of a pipe O is connected. The free end of this pipe O discharges into an elongated exhaust passage K⁹ open at one end, and this passage contains a series of blades K forming pockets 130

K' between them. The exhaust products of combustion will be discharged by the pipe O into the pockets K' and impinge against the blades K , and thus the exhaust products are utilized in adding propelling power to the engine. It will be understood that the central shaft D may be mounted to rotate and the casing M rigidly connected with the heads b and d of the frame.

10 Various other changes might be made in the details of construction of my invention without departing from the spirit thereof or limiting its scope, and hence I do not wish to restrict myself to the precise details herein 15 set forth.

Having fully described my invention what I claim as new and desire to secure by Letters-Patent, is:—

1. In an internal combustion engine, the 20 combination with a fixed frame comprising two heads and a fixed shaft connecting them, of a rotary member disposed between said heads and comprising a revoluble casing, a pair of cylinders secured within said casing, 25 two oppositely moving pistons in each of said cylinders, gearing mounted in said casing and operatively connected with said pistons, and a gear on the fixed shaft operatively associated with said gearing.

30 2. In an internal combustion engine, the combination with a fixed frame, of a rotary member mounted therein and operatively associated therewith, said rotary member including a plurality of engine units, valve 35 mechanism for each of said units, a tube having ports communicating with the valve mechanisms, a valve tube movable within said first-mentioned tube and having ports of various lengths, means for supplying motive fluid to said tubes, and means for moving said valve tube to include the several engine units successively into service or to 40 successively exclude said engine units.

3. In an internal combustion engine, the 45 combination with a fixed frame, of a rotary member mounted therein and including a plurality of engine units operatively associated with the fixed frame, valve mechanisms for said engine units, a tube having 50 ports communicating with the valve mechanisms of the several engine units, a valve tube movable longitudinally in said first-mentioned tube, and having ports of various lengths, a foot lever mounted on the 55 fixed frame, a collar movable with the rotary member, connections between said collar and the foot lever, a lever pivoted to the rotary member and said collar, and a rod connecting said last mentioned lever with 60 said valve tube.

4. In an internal combustion engine, the combination with a fixed frame comprising two heads and a fixed shaft connecting them, of a rotary casing disposed between said 65 heads, a pair of cylinders secured within

said casing, two oppositely moving pistons in each of said cylinders, means for supplying an explosive charge between said pistons and for exhausting the products of combustion, oscillatory cross-heads connecting the 70 pistons in the respective cylinders, a gear on the fixed shaft, larger gears meshing with the gear on the fixed shaft, and connections between said cross heads and said larger gears for driving the latter.

75

5. In an internal combustion engine, the combination with a fixed frame comprising two heads and a fixed shaft connecting them, of a rotary casing mounted between said heads, a pair of cylinders secured in said 80 casing, two oppositely moving pistons in each of said cylinders, oscillatory cross heads connected with the pistons in the respective cylinders, two crank shafts mounted in said casing and operatively connected 85 with said cross heads, gears carried by said crank shafts, and a smaller gear secured to the fixed shaft and meshing with the gears on the crank shafts.

6. In an internal combustion engine, the 90 combination with a fixed frame comprising two heads and a fixed shaft connecting them, of a rotary casing between said heads, a pair of cylinders secured in said casing, two oppositely moving pistons in each cylinder, 95 cross heads connected with the pistons in the respective cylinders, crank shafts mounted in said casing, gears secured to said crank shafts, a smaller gear on the fixed shaft and meshing with the gears on the crank shaft, 100 oscillatory arms connected with said cross heads, and links connecting said oscillatory arms with the crank shafts.

7. In an internal combustion engine, the combination with a fixed frame comprising 105 two heads and a fixed shaft connecting them, of a rotary casing between said heads, a pair of cylinders secured in said casing, two oppositely moving pistons in each of said cylinders, oscillatory cross heads connected with said pistons, crank shafts mounted in the casing, connections between said crank shafts and said oscillatory cross heads, gears on said crank shafts, a gear on the fixed shaft and meshing with the gears 110 on the crank shafts, valve mechanism between said cylinders, a cam shaft for operating said valve mechanism, and gearing between said cam shaft and one of said crank shafts.

115

8. In an internal combustion engine, the combination with a fixed frame comprising two heads and a fixed shaft connecting them, one of said heads having an elongated exhaust passage and a plurality of blades in 125 said passage, of a rotary member between said heads, cylinders constituting parts of said rotary member, pistons in said cylinders, gearing between said pistons and the fixed shaft, means for supplying explosive 130

charges to said cylinders, and an exhaust pipe for receiving products of combustion from said cylinders, said exhaust pipe disposed to discharge the exhaust products of combustion against the blades in said exhaust passage.

In testimony whereof, I have signed this

specification in the presence of two subscribing witnesses.

ARTHUR M. SNYDER.
